UNITED STATES PATENT OFFICE.

FREDERICK L. G. STRAUBEL, OF GREEN BAY, WISCONSIN.

FILING TRAY.

Application filed February 10, 1923. Serial No. 616,180.

To all whom it may concern:

Be it known that I, FREDERICK L. G. STRAUBEL, a citizen of the United States, residing at Green Bay, the county of Brown, 5 and State of Wisconsin, have invented certain new and useful Improvements in a Filing Tray; and I do hereby declare the following to be a full, clear, and exact description of the invention, such as will enable 10 others skilled in the art to which it appertains to make and use the same.

My invention relates to file drawers and trays for use in the same and particularly to the class of filing trays used in connection 15 with card indexes. Where such indexes are stored in sections of filing cabinets, it has long been customary to mount each card file in a separate drawer. This practice not only involves a considerable expense on account 20 of the cost of the woodwork for each such card drawer, but also wastes a good deal of space through the thickness of the partitioning between adjacent drawers, and gives the cabinet an unsightly appearance whenever 25 one or more such card drawers have been withdrawn from the same for use. Furthermore, the compartments or pigeon-holes as planned in a cabinet for this purpose will only fit the file drawers for one 30 particular size of card, so that they are not interchangeable and so that they require both the factory and the dealers to carry a wide variety of corresponding cabinets or 35 cabinet sections to meet the varying requirements.

The present invention aims to overcome these objections to the present practice by providing a file drawer and tray arrangement which will permit various sizes of card 40 trays to be used interchangeably in a single drawer; which will readily permit any such card trays to be withdrawn from the drawer and which will permit such withdrawal without removing the drawer from the cabinet; which will hold all of the cards at a 45 convenient height while the trays are in the drawer, and which will be particularly suitable for a metal tray construction. Still further objects will appear from the following specification and from the accompanying drawings, in which

Fig. 1 is a fragmentary vertical section through a filing cabinet embodying my invention, showing a drawer extended for 50 convenient access to two card-file trays

mounted therein, and having the nearer side of the drawer broken away to show the sides of card trays of two sizes.

Fig. 2 is another side elevation of the same drawer, with a portion of the nearer side broken away and with one of the card trays partly lifted or rocked out of its normal position to permit of removing it from the drawer.

Fig. 3 is a vertical transverse section 65 through the same drawer and trays, taken along the line 3—3 of Fig. 1 but with the cards shown in Fig. 1 omitted.

Fig. 4 is an enlarged fragmentary view of the upper rear corner of Fig. 2, showing 70 the pivoting arrangement which permits the tilting of the card tray.

Fig. 5 is an enlarged perspective view of the front end member of one of the card files of Figs. 1 to 3 inclusive.

Fig. 6 is a central, vertical and longitudinal section through the forward portion of another file drawer embodying my invention and having a different arrangement of the finger hold from that shown in Figs. 1, 2 80 and 5.

In the illustrated embodiments, I am picturing my invention as used in connection with file drawer cabinets having relatively large drawers, or drawers each of considerably larger size than required for a single ordinary card file. Thus, Figs. 1 to 3 inclusive show a drawer of rectangular section having its sides, bottom and end made of steel and having a wooden front. This front 90 desirably projects at all four of its edges beyond the sides and bottom of the drawer so as to overlap the edges of the opening in which the drawer is slid able and to afford a dust-tight closure when the drawer is slid back. Within this drawer I am showing two card files of different sizes as removably mounted, each of these card files being supported within the drawer only adjacent to the tops of its front and rear ends. For this purpose, I provide the front 1 of each such drawer with a forwardly projecting flange 2, which flange desirably is substantially horizontal when the tray is in position and normally rests on a ledge 3 formed by undercutting the wooden front 4 of the drawer at its top along its inner face. The rear end 5 of the file drawer is also equipped with a supporting flange, here shown as the rearwardly projecting flange 6 which normally 110

has a substantially horizontal position and which rests upon the rolled upper edge 7 of the rear end 8 of the drawer.

- With the parts thus arranged, it will be seen from Fig. 1 that the file trays are suspended within the main drawer 9 from their flanges and by employing a uniform spacing between the supporting flanges 2 and 6 of the various card file trays and the tops of the cards for which these are respectively suited, I cause all of the cards to be supported at the same height within the drawer regardless of the different sizes of the cards. Consequently, they will all be accessible with equal convenience when the drawer is partly extended, although the bottoms of the card trays may be spaced by varying distances from the bottom of the drawer in which these are supported.
- To facilitate the withdrawing of the card trays from the drawer and their return to the drawer, I am showing the forward end 1 of each drawer as sloping rearwardly from its juncture with the supporting flange 2 to the bottom of the drawer as shown in the drawings, so that there normally is a considerable space between the lower part of the forward end of each card tray and the rear face of the drawer front. The spacing thus provided permits each tray to be swung upwardly with a pivotal movement about the rolled edge 7 on the rear of the drawer after the manner shown in Fig. 2. Consequently, each card tray can be tilted upwards sufficiently to permit it to clear the top of the front of the drawer when the drawer is only partly extended after the manner shown in Fig. 2, so that the drawer never needs to be removed entirely from the cabinet for removing or replacing the card trays. Furthermore, the arrangement thus disclosed will facilitate the removal and replacing of the trays even if the entire drawer should be withdrawn from the cabinet.

To facilitate the above described pivotal lifting or rocking of the card trays, I provide each tray with a suitable fingerhold, and where each tray is to be labeled, I desirably provide this fingerhold by employing a label holder 11 mounted on the frontal supporting ledge 2 and projecting rearwardly beyond the front 1 of the drawer. Thus arranged, it will be evident from Figs. 2 and 5 that the rearward projecting of the label holder 11 not only affords desirable added space for a suitable label card, but also affords a ledge or shoulder facing the interior of the tray and under which the user may readily get a finger hold for lifting the tray out of its position in the drawer.

As a further convenience in construction, I desirably employ tray end members each having both a supporting ledge, a bottom ledge and a pair of side ledges in integral

formation. For example, Fig. 5 shows a forward end construction of this kind including side ledges 12 between which the trough-shaped drawer, side and bottom piece 13 is inserted, and shows a rear end member having corresponding side pieces 14. Then I also desirably secure a cushioning strip 15 (of felt or the like) to the bottom ledge of each such end-piece after the manner shown in Fig. 5, so that each card tray can be set down on delicate furniture without having any metal part scratch the latter.

While each tray end is thus equipped with a flange or supporting portion projecting 80 edwardly of the tray, the rear end is desirably less tall than the forward end, and the drawer in which such files are to be used desirably has its back 8 of less height than the height to the ledge 3 on the drawer front. This difference in heights permits the fingerhold to be disposed for easy access above the tops of the cards even when the tray is well filled.

However, I do not wish to be limited to the rolled edge affording part of the pivoting arrangement, or to the combined label holder and fingerhold, or to other details of construction and arrangement as just disclosed, it being obvious that these might be 95 greatly varied without departing either from the spirit of my invention or from the appended claims. For example, Fig. 6 shows a portion of the card tray construction in which the front 1 is bent rearwardly 100 to afford a fingerhold ledge 16 and is then recurved forwardly to afford a forwardly projecting supporting flange 17.

I claim as my invention:—

1. The combination with a drawer, of a card tray having each end thereof equipped with an outwardly directed flange adapted to seat on a wall of the drawer, one of the said flanges and the drawer wall engaged thereby being arranged to afford a rocking movement of the tray about the wall portion engaged thereby, the opposite end of the tray being spaced from the adjacent wall below the flange engaging the latter so as to permit the said rocking movement.

2. The combination with a drawer, of a card tray having each end thereof equipped with an outwardly directed flange adapted to seat on a wall of the drawer, the flange at one end of the tray and the drawer wall engaged thereby being arranged to afford a rocking movement of the tray about the wall portion engaged thereby; the opposite end of the tray being spaced from the adjacent wall below the flange engaging the latter so as to permit the said rocking movement, the last-named end of the tray being provided with a fingerhold for raising that end to effect such rocking.

3. A drawer and tray combination as per

claim 2, including a label holder carried by the front end of the tray, a portion of the label holder being disposed for affording the said fingerhold.

5. 4. A drawer and tray combination as per claim 2, including a label holder mounted on the flange on the last-named end of the tray and projecting inwardly of the tray beyond the top of that end of the tray so as 10 to afford a fingerhold for lifting the tray to produce the said rocking movement.

5. The combination with a drawer having a front of greater height than its back and having a ledge below the top of its front, 15 of a card file tray having the top of its back equipped with means for engaging the back of the drawer and for permitting a rocking of the tray about its said engagement with the back of the drawer, the tray having 20 means at its front end for engaging the said ledge and means affording a fingerhold whereby the said front end may be lifted to rock the tray.

6. A file tray for suspended support in a 25 drawer, comprising a tray having its rear end equipped at its top with a rearwardly projecting ledge for supporting engagement with one drawer wall and having a taller forward end sloping upwardly forward toward the opposite drawer wall, the forward tray end having at its upper end a forwardly directed projection disposed for seating on a portion of the said other drawer wall.

7. A file tray for suspended support in a

drawer, comprising a tray having its rear end equipped at its top with a rearwardly projecting ledge for supporting engagement with one drawer wall and having a taller forward end sloping upwardly forward toward the opposite drawer wall, the forward tray end having at its upper end a forwardly directed projection disposed for seating on a portion of the said other drawer wall and having a rearwardly directed shoulder formation affording a fingerhold for lifting that end of the tray.

8. A forward end member for a filing tray, comprising in rigid formation an end piece sloping forwardly upward from the bottom of the tray, a forwardly directed projection at the top of the end piece, and a bottom flange secured to the bottom of the tray, the end piece having a shoulder formation facing the interior of the tray and affording a fingerhold for lifting that end of the tray.

9. A forward end member for a filing tray, comprising in rigid formation an end piece sloping forwardly upward from the bottom of the tray, a forwardly directed projection at the top of the end piece, and a shoulder adjacent to the said top and accessible by reaching behind the said top, the shoulder affording a fingerhold for lifting that end of the tray.

Signed at Green Bay, Wisconsin, January 30, 1923.

FREDERICK L. G. STRAUBEL.
